[57] CLAIM

The ornamental design for a classical guitar peghead, as shown and described.

DESCRIPTION

FIG. 1 is a front view of a classical guitar peghead of the present invention.

FIG. 2 is a right side view (relative to FIG. 1) of the classical guitar peghead of the present invention. The left side view would be a mirror image.

FIG. 3 is a fragmentary cross sectional view showing the inner cutout area taken along line 3—3 of FIG. 1.

FIG. 4 is a back view of the classical guitar peghead of the present invention.

FIG. 5 is an upper end view of the classical guitar peghead; and,

FIG. 6 is a view of the lower end of the classical guitar peghead of FIG. 1, with the neck cut-away.

The broken lines shown in FIGS. 1, 2 and 4 define the bounds of the claimed design and form no part thereof.
